UNITED STATES PATENT OFFICE.

EDWARD C. HAVILAND, OF NEW YORK, N. Y., ASSIGNOR TO VAN KANNEL REVOLVING DOOR COMPANY, OF NEW YORK, N. Y., A CORPORATION OF NEW JERSEY.

PIVOTING DEVICE FOR FOLDABLE REVOLVING DOORS.

1,010,627.

Specification of Letters Patent.

Patented Dec. 5, 1911.

Application filed March 14, 1911. Serial No. 614,350.

To all whom it may concern:

Be it known that I, EDWARD C. HAVILAND, a citizen of the United States, residing at 290 East One Hundred and Thirty-fourth street, 5 New York, county of New York, and State of New York, have invented certain new and useful Improvements in Pivoting Devices for Foldable Revolving Doors, fully described and represented in the following 10 specification and the accompanying drawings, forming a part of the same.

This invention relates to that class of foldable revolving doors, in which the wings which revolve within a segmental door-casing are jointed together so as to be folded 15 flat, and thereafter moved to one side of the door-casing so as to leave an unobstructed passage through the same. In such constructions, two of the wings are rigidly connected 20 and projected upon opposite sides of the center bolts upon which the wings turn, and in the present invention transfer-bolts (or bolts upon which the folded wings may turn to be 25 swung close to the casing) are fitted to move vertically in one of the rigid wings near its outer edge, and fitted to sockets in the floor and ceiling of the casing near one edge of the casing segment, and these transfer-bolts are connected with the pivot-bolts by mechanism 30 which prevents the retraction of the pivot-bolts or transfer-bolts from their sockets until the others are inserted in their sockets. Without such a mechanism connecting the pivot-bolts and transfer-bolts, either 35 might be withdrawn before the other was seated in the sockets, and the wings would then be unsupported and liable to fall, especially if a gust of wind should strike them in such unsupported condition.

40 By my construction, the weight of the folded wings is always supported upon one pair or the other of the two sets of bolts, as it is impossible to retract both simultaneously. Any suitable mechanism for thus 45 connecting the pivot-bolts and the transfer-bolts may be employed, two forms being illustrated in the annexed drawing, in which—

Figure 1 is a plan showing the casing with 50 the wings represented in full lines in their operative position, and in dotted lines in their shifted position. Fig. 1^a shows a means to suspend the wings. Fig. 2 is an elevation of the wings removed from the 55 casing; Fig. 3 is an elevation of one of the

wings with the floor and ceiling in section, and the two sets of bolts directly connected by levers; and Fig. 4 is a similar view with a locking-bar to govern the transfer-bolts and actuated by the pivot-bolts, a portion of 60 the wing adjacent to the pivot-bolt being broken away to show the concealed bell-crank.

In Fig. 1, *a* designates the usual casing formed with opposite segments; *b* the two wings connected rigidly together, and *c* the wings hinged thereto near the center so that they can be folded, as indicated in dotted lines *b'* and *c'* adjacent to one of the casing segments. The wings *b* and *c* are shown 65 in their operative position with ties *a'* connecting them together, with one of the rigid wings *b* in line with a socket *d* in the floor of the casing, with a transfer-bolt *e* fitted to such socket. The pivot-bolts *f* at the center 70 of the wings are shown movable inwardly in Fig. 3, by means of links *g* jointed to the bolts and to a crossbar *h* which is fulcrumed upon one of the fixed wings intermediate to its top and bottom, and provided with means 75 for turning it when desired, in the usual manner. Packing flaps *f'* are shown at the sides of the wings. The transfer-bolts *e* are shown in Fig. 3 connected with the pivot-bolts *f* by a lever *i* pivoted upon one of the 80 wings *b* and jointed to each of the bolts by a slot *j* and stud *k*. When the pivot-bolts are advanced, as shown in Fig. 2, the transfer-bolts are retracted; and the opposite is true 85 when the pivot-bolts are retracted. In transferring the wings to the side of the casing, as indicated by the dotted lines *b'*, *c'*, in Fig. 1, one of the rigid wings is moved until the transfer-bolts come coincident with their 90 sockets *d*, *d'* in the floor and ceiling, and the support of the rigid wings can then be transferred from the pivot-bolts to the transfer-bolts; but owing to the mechanical connection between the two, shown in Fig. 3, the pivot-bolts cannot be retracted from their 95 sockets without advancing the transfer-bolts into their sockets, so that the wings are securely supported when the pivot-bolts are retracted. The folded wings are then in 100 readiness to swing parallel with the side of the casing, as indicated by the lines *b'*, *c'*, and remain secured by the transfer-bolts, because the latter cannot be retracted until the pivot-bolts are swung back over their sockets and are advanced into the same.

Fig. 4 shows a locking-bar *l* actuated by connection with one of the pivot-bolts, for preventing the retraction of the transfer-bolt from its socket; but leaving the retraction of the transfer-bolt to be effected by hand when the pivot-bolts have been projected, which operation retracts the locking-bar from interference with the transfer-bolt. The locking-bar *l* is movable longitudinally across the inner end of the transfer-bolt *e*, and is connected with the pivot-bolt *f* by a bell-crank *m*, and is shown projected across the path of the transfer-bolt by the retraction of the pivot-bolt. The locking-bar and bell-crank are both concealed within the thickness or substance of the wing *b*, but the portion of the wing adjacent to the bell-crank is broken away to show its connection with the other parts.

In Fig. 3, the levers *i* are shown exposed, as well as the links *g* which move the pivot-bolts, but such parts may obviously be concealed within the door, if desired, the same as the locking-bar and its bell-crank.

In revolving doors having foldable wings which are transferred to the side of the casing, as shown in Fig. 1, the weight of the wings when revolving is commonly suspended from an anti-friction journal above the upper pivot-bolt; but such arrangement is not shown in Figs. 2, 3 and 4, as the means for sustaining the weight of the doors when rotating is immaterial. I have, however, in Figs. 1 and 1^a shown a means of suspending the wings detachably from a center king-bolt, the top of the wings *b* at the center being provided with a rabbeted socket or hanger *n* adapted to fit a collar *o* upon the lower end of the king-bolt *p*. The king-bolt is journaled in the beam *q* over the ceiling *e'* and has a socket in the lower end adapted to receive the upper pivot-bolt *f*. The hanger is open at one side, as shown in Fig. 1, to permit the wings to be swung off of the king-bolt when the pivot-bolt *f* is retracted, and the wings are pivoted upon the transfer-bolts. The bolt *f* prevents any displacement of the hanger from the king-bolt when the wings are arranged to revolve in the casing.

Fig. 2 shows the wings detached from the casing, to show the slight change caused in the wings by the addition of my improvements; the wing *b* at the right hand side of the figure showing the visible parts of the housings *g'* for the transfer-bolts, and all else being concealed from view.

Having thus set forth the nature of the invention what is claimed herein is:

1. In a foldable revolving door, the combination, with foldable wings, of pivot-bolts at the center of the wings, transfer-bolts movable vertically in one of the wings near the edge, and mechanism controlled by the pivot-bolts for locking the transfer-bolts when the pivot-bolts are retracted.

2. In a foldable revolving door, the combination, with foldable wings, of a pivot-bolt at the center of the wings, transfer-bolts movable vertically in one of the wings near the edge, and mechanism connecting the pivot-bolts and transfer-bolts, for retracting one when the other is advanced.

3. In a foldable revolving door, the combination, with foldable wings, of a pivot-bolt at the center of the wings, transfer-bolts movable vertically in one of the wings near the edge, means between the top and bottom of the door for projecting the two pivot-bolts simultaneously, and means connected with the two pivot-bolts for simultaneously imparting a reverse movement to the transfer-bolts.

4. In a foldable revolving door, the combination, with foldable wings, of pivot-bolts at the center of the wings, concealed transfer-bolts movable vertically within one of the wings near the edge, and mechanism connected with the pivot-bolts and concealed within such wing for locking the transfer-bolts when the pivot-bolts are retracted.

In testimony whereof I have hereunto set my hand in the presence of two subscribing witnesses.

EDWARD C. HAVILAND.
